United States Patent Office

Des. 223,931

Patented June 20, 1972

223,931

MAGNETIC TAPE CASSETTE TRANSPORT

Hari K. Matsuda, Evanston, Ill., assignor to Ampex Corporation, Redwood City, Calif.

Filed June 3, 1971, Ser. No. 149,882

Term of patent 14 years

Int. Cl. D14—01

U.S. Cl. D26—14

FIG. 1

FIG. 2

FIG. 1 is a front, top and right side perspective view of a magnetic tape cassette transport, showing my new design; and

FIG. 2 is a bottom, rear and left side perspective view. I claim:

The ornamental design for a magnetic tape cassette transport, substantially as shown and described.
